(57) **CLAIM**

The ornamental design for a folding storage box as shown and described.

DESCRIPTION

FIG. 1 is a perspective view of a folding storage box showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is an enlarged view of portion of FIG. 1; and,

FIG. 10 is a third perspective view of FIG. 1 shown in a closed position.

The broken lines in the drawings are for the purpose of illustrating portions of the folding storage box and form no part of the claimed design. The dot-dash broken lines in the drawings indicates cutoff boundaries for the enlarged detailed portion views and form no part of the claimed design.

1 Claim, 10 Drawing Sheets
